UNITED STATES PATENT OFFICE.

VACLAV J. HAJNÝ, OF BROOKFIELD, ILLINOIS.

DESIGN FOR A PLAQUE.

Application filed May 18, 1928. Serial No. 26,750. Term of patent 3½ years.

To all whom it may concern:

Be it known that I, VACLAV J. HAJNÝ, a citizen of the United States, residing at 210 North Forest Avenue, in the town of Brookfield, county of Cook, and State of Illinois, have invented a new, original, and ornamental Design for a Plaque, of which the following is a specification, reference being had to the accompanying drawing, forming part thereof:

The roughened surface of the backing is continued about the shield element and around the floral relief work.

I claim:

The ornamental design for a plaque as shown and described.

VACLAV J. HAJNÝ.
